UNITED STATES PATENT OFFICE.

ROBERT SIMON, OF WEEHAWKEN, NEW JERSEY.

KNIFE-SHARPENER FOR DOUBLE-PILE-FABRIC LOOMS.

SPECIFICATION forming part of Letters Patent No. 399,293, dated March 12, 1889.

Application filed July 27, 1887. Serial No. 245,404. (No model.)

To all whom it may concern:

Be it known that I, ROBERT SIMON, of Weehawken, Hudson county, New Jersey, have invented certain new and useful Improvements in Sharpeners for Knives in Velvet and other Looms, of which the following is a full, clear, and exact description.

Heretofore in velvet-ooms, plush-ooms, and the like, in which a double fabric is woven to be separated by a pile-cutting knife, the knife for cutting the pile has been commonly passed over a yielding hone or sharpener. The continued passing of the knife over the sharpener would wear a groove in the latter, and also leave thereon a deposit of steel, &c., all of which would interfere with the sharpening of the knife.

The object of my invention is to overcome these objections and to provide a movable sharpener, so that the knife will pass over a different part of the sharpener after each cut in the fabric, and thereby cause an even wear on the sharpener.

The invention consists in the combination, with a movable hone-carrier, of mechanism for intermittently moving it and changing its position, so as from time to time to present a different portion of its surface to contact with the knife.

The invention also consists in special means for moving the hone-carrier after each passage of the knife, and in details of construction and combination of parts, as will be more fully hereinafter set forth.

Reference is to be had to the accompanying drawings, forming part of this specification, in which one mode of carrying my invention into effect is illustrated; but other mechanism for moving the hone-carrier may be used and will readily suggest itself to any skilled mechanic.

Figure 1 is a vertical cross-section of part of a loom, taken on the line $c c$ of Fig. 2, looking in the direction of the arrow a^2 , showing a pair of my improved knife-sharpener in position in the loom and the position of the knife with relation to the same. Fig. 2 is a plan view of a portion of a loom, showing a pair of my improved knife-sharpener. Fig. 3 is a view of one of my improved sharpener

ers and connected devices, looking in the direction of the arrow b^2 , Fig. 2. Fig. 4 is a vertical section of my improvement on the line $k k$, Fig. 3, looking in the direction of the arrow d^2 ; and Fig. 5 is a side view of the cam used to move the slide carrying the sharpening-stone.

A in the drawings represents a portion of the frame of a loom of the class on which velvet or the like is woven. B is a knife carried by a clamp, a , the end b of which clamp is adapted to slide in a groove, d , in the loom-frame A. The clamp a is secured to a band or other carrier, e , which has reciprocating motion imparted to it by suitable means. This gives the knife B a to-and-fro motion. D represents a piece of velvet, which in Fig. 1 is shown as being wound on two cloth-beams, f , after the pile has been cut by the knife B. E represents part of the batten of the loom. These parts are all of well-known construction and need no further description.

F is a slide mounted in bearings in a frame, G, which is attached to the frame A of the loom. The frame G carries an upwardly-projecting lug, g , which is adapted to be secured to a projection, h , on a cross-beam, a^3 , of the frame A. (Best seen in Fig. 1.) The lug g has a slot, through which passes a bolt, i , said bolt also passing through a hole or slot in the projection h to permit a proper adjustment of the frame G. The slide F carries an upright or projection, l , to which is pivoted at l^2 the lever II. On one end of the lever II is secured a hone or other sharpener, I. Near the opposite end of the lever or hone-carrier II is attached a spring, m , the other end of which is attached to the slide F or to the frame.

In Figs. 1 and 2 of the drawings are shown two frames, G, each carrying a slide, F, lever II, and sharpener I. In Fig. 1 these frames are shown arranged at an angle to each other. The sharpener I on one lever II, Figs. 1 and 2, is shown on the under side of said lever, while on the other lever II it is shown on the upper side. The spring m at the left in Fig. 1, at the right in Fig. 2, and in Figs. 3 and 4 is shown attached to the lever II outside of the pivot l^2 , which tends to raise the long arm of the lever II, and thereby the sharpener

I. The spring m in the foreground in Fig. 1 and at the left in Fig. 2 is shown connected to the lever H between the sharpener I and its pivot l^2 . This tends to lower the long arm 5 of the lever H , and thereby the sharpener I. A stop, n , limits the movement of the lever H on its pivot. The sharpeners I may also rest in part upon a bevel, o , on the cross-bar a^3 in the frame A, Figs. 1 and 2. The slide F carries a downwardly-projecting pin, p , which bears against the face of a cam, J, rigidly secured on a shaft, q , journaled in bearings in the frame G. The shaft q also carries a worm-wheel, r , which gears with a worm, s , that is journaled in the frame G. On one end of the worm s is secured a ratchet-wheel, L. A lever, t , is pivoted to the frame G near the ratchet-wheel L, and carries a pawl, u , which is adapted to engage said ratchet-wheel L. A spring, v , secured to the frame G, acts upon the lower end of lever t . A spring-click, w , acts against the ratchet-wheel L to prevent reverse motion thereof. M is a bracket secured to the batten and adapted to actuate the lever t . I have described these parts as applying to one instrument, although in Figs. 1 and 2 are shown two instruments. This description applies with equal force to both.

The operation is as follows: Suppose the knife B to be in the left-hand part of Fig. 2. The knife B now begins to move in the direction of the arrow f^3 , Fig. 2. It first passes along the face of the sharpener I which is on the underside of the one lever H, and then over the face of the sharpener I which is on the top of the next lever H. As the knife continues to move, it cuts the velvet D in the ordinary manner. At the first throw of the batten to 40 beat home the weft the bracket M strikes the end of the lever t , which, through pawl u , moves the ratchet-wheel L a suitable distance. This movement imparts motion to the cam J, which in turn, pressing upon the pin p , moves the slide F, and thereby the sharpener I, in the direction of the arrow b^2 , Fig. 2, a slight distance. As the knife comes back to the first position described, it passes over the sharpeners II; but as said sharpeners have been moved a slight 45 distance, as stated, the knife B does not touch them at the same point it did before. Each time the batten is moved to beat the weft the sharpeners are moved a short distance until the cam J has made, say, one revolution, and 50 until the pin p comes opposite the narrow or receding part x of said cam J. At this moment a spring, N, secured at one end to the slide F, and at the other end to a projection, y , on the frame G or frame A, draws the said slide F 55 backward or in the reverse direction to which it had been moving, ready to start forward again by the motion of the batten M, the lever t , and thereby the cam J, as before stated. From this it will be seen that the knife passes 60 over a different part of the sharpener at each 65

passage. This prevents the formation of a groove in the sharpener, as is the case with the stationary sharpeners.

By placing the sharpeners I I at an angle, and with one at the top and the other on the 70 under side of the levers H H, I am enabled to sharpen the knife with a proper bevel. By using two sharpeners in one loom both sides of the knife will be sharpened at one passage of the knife. By resting the sharpeners on 75 the beam a^3 the proper angle will be insured, and the sharpeners will always be in their correct positions. The hone-carrier may be operated by other means than by the batten and lever, if desired.

Having now described my invention, what I claim is—

1. The combination of the reciprocating cutter B with the sharpener I and means, substantially as herein described, for moving 85 said sharpener by degrees into the path of the knife, so that said knife will pass over a different part of the stone after each cut in the fabric, as set forth.
2. The stationary frame G, combined with 90 the slide F, means for intermittently moving the same, the lever H, and with the sharpener I, carried by said lever, substantially as described.
3. The slide F, carrying the lever H, combined with said lever and with means for intermittently moving the said slide, and with the sharpener I, substantially as described.
4. The pivoted lever H and sharpener I, combined with means, substantially as described, for supporting said lever and for moving 100 said lever intermittently, as set forth.
5. The slide F and a spring for moving the same, the frame G, lever H, the sharpener I, and pin p , in combination with the cam J, and with means, substantially as described, for moving said cam, as set forth.
6. The combination of the slide F, lever H, the sharpener I, spring N, pin p , cam J, worm s and worm-gear r , ratchet-wheel L, 110 lever t , and pawl u , for moving the same, the lever t being adapted to be actuated from the batten E, substantially as described, and for the purposes set forth.
7. The combination of the batten having a 115 lever-actuator, the slide F, and the movable hone-carrier H, carried by said slide, with the reciprocating knife B, and with a cam, worms r and s , ratchet-wheel L, pawl u , and lever t , intermediate between said batten and said hone-carrier, for moving the same by the batten, as specified.
8. The combination, in a loom, of the reciprocating knife B with two movable hone-carriers, H H, and mechanism, substantially as 125 described, for moving both hone-carriers from time to time, so that the knife will pass over a different part of the hone after each cut in the fabric, substantially as described.
9. The slide F and movable hone-carrier 130

II, carried thereby, combined with the knife B and the rest or support a^3 for said hone-carrier, and with a cam connected with the slide F, and a lever, and intermediate mechanism connecting the lever with the cam to shift the position of said hone-carrier, so that the knife will pass over a different part of

the hone after each cut in the fabric, and with the batten for actuating the lever, as specified.
